ABRASIVE CONTROL UNIT

Lloyd L. Hobson, Marshall, Mich., assignor of
one-half to Harry S. Toy, Detroit, Mich.

Application December 12, 1940, Serial No. 369,861

6 Claims. (Cl. 51—9)

My invention pertains to material dispersing apparatus and more particularly to abrasive distributing devices.

It is an object of my invention to provide an improved centrifugal material distributing apparatus.

It is also an object of my invention to provide improved rotary material distributing devices of simple, durable construction comprising means controlled for restricting the flow of material from the apparatus during predetermined portions of the circle of rotation of the apparatus.

It is a further object of my invention to provide rotary material distributing apparatus comprising, a rotatable material distributing housing which is hollow and has material distributing apertures opening outwardly for distributing material from the central portion of the housing as it rotates, and also having an aperture closing member adjacent each aperture for closing and opening the apertures as the housing rotates, and control means for controlling the opening and closing of each aperture during predetermined portions of the circle of rotation.

Further objects and advantages are within the scope of my invention, such as relate to the arrangement, operation and function of the related elements of the structure, to various details of construction and to combinations of parts, elements per se, and to economies of manufacture and numerous other features as will be apparent from a consideration of the specification in conjunction with the drawings disclosing a specific embodiment of my invention, similar reference characters being applied to corresponding elements throughout, and in which:

Fig. 1 is a sectional view taken axially along the axis of rotation and showing rotary distributing apparatus arranged in accordance with my invention;

Fig. 2 is an enlarged sectional view on line 2—2 thereof; and

Fig. 3 is an enlarged view, being a cross section through the central portion of one of the slot closing members 45.

Referring more particularly to the figures of the drawings, I have illustratively disclosed a preferred embodiment of my improved material dispersing apparatus comprising a drive shaft 11 which is journaled for rotation on a horizontal axis in suitable bearing 13, rising from a support 14, located on the floor 15 and it may be driven by an electric motor or other motive means in any suitable manner. The other end of the drive shaft 11 extends from the bearing and has

5 mounted thereon for support and rotation a hollow material distributing housing 16 comprising an end wall 16' and a cylindrical portion 17, the end wall being therein secured in any suitable manner as by tack welding. The housing 16 has spaced abrasive guides 18 of a substantially triangular cross section, see Fig. 2, secured therein, as by means of screws 18', as shown, or any other suitable means. The cylindrical portion 17 of said housing 16 has material distributing apertures 19 opening outwardly for delivering material by centrifugal force from the inside as the housing rotates. The material dispersing apertures 19 may take the form of axially elongated 10 slots spaced apart circumferentially in the side walls thereof, said slots being located at the points between the guides 18. The apex of each guide 18 is turned inwardly and is provided with retaining bars 21 extending across from each apex to each adjacent apex where these may be secured, as by welding, to prevent the slot closing members from falling inwardly when the device is stationary. At one end the housing 16 is open for receiving material from any source of supply. The closed end or wall 16' of the housing is secured to the end of the shaft 11, as by a screw 25 extending into a threaded aperture therein. If desired, the end wall 16' of the housing may be securely interlocked to rotate with the shaft 11 as by suitable interlocking parts (not shown) 15 provided on these two elements for interconnection therebetween, but this is not necessary where the apparatus is utilized for light work.

On the end of the shaft 11 adjacent the material distributing housing a collar 27 is secured, as by a set screw or key 28, and carries an attaching flange 29 projecting laterally to a substantially greater diameter than the housing.

One form of a device in which my dispersing apparatus may be used will now be described. A circular side wall plate 31 may be provided which fits snugly over the peripheral surface of the housing and is secured to the attaching flange 29, as by means of screws 32. A second annular side wall 33 may be provided which fits snugly over the housing around the opposite end and in spaced relation from the first mentioned side wall. Secured between the said annular side walls, as by welding, are a plurality of spaced partitions 37 which extend radially, one from between each slot 19 in the material dispersing housing and in this manner a radial dispersing passage 39 is formed, open from each slot. Material or abrasive to be dispersed is fed into the open end of the housing as by a conduit 41 lead-

ing the material down by gravity from a hopper 43 and connecting into the open end of the housing.

For opening and closing the slots 19 in the peripheral portion 17 of the housing 16 as it rotates, a slot closing member 45 is provided adjacent each slot. As shown, each slot closing member 45 is an axially elongated bar of generally triangular cross-section of a suitable width for closing the adjacent aperture or slot. In operation centrifugal force throws the bars 45 outwardly and the retainer bars 21 hold these where the housing is not rotating.

Control means is provided for controlling the opening and closing of each slot during predetermined portions of its circle of rotation, comprising a rotatively journaled control member 47 from which a flexible member 49, such as a chain, connects to each slot closing member. The outer end of the outer link of each piece of chain 49 is pivotally connected to the center of one of the slot closing bars 45 in any suitable manner, as by insertion into a shallow slot 50 where it is pivotally connected by a pivot pin 51 secured thereacross, as by welding, to the bar. Although the flexible connector member 49 is shown as a large chain for clearness, a small chain of greater flexibility is preferably utilized in actual practice. The chains 49, not under tension, have been broken away and represented as dotted lines to more clearly indicate this condition. The rotatable control member 47 may consist of two rings 53 and 55 having a plurality of pivot pins 57 extending therebetween in circumferentially spaced relation. The inner end of the inner link of each of the pieces of chain 49 is pivotally received on one of the pins 57. The control member 47 is rotatably journaled in the housing upon an off-set eccentric 59 of a shaft 61 which extends out of the open end of the housing, passing through the side wall of the conduit 41 to a suitable bracket 63 in which it is firmly secured as by a clamp plate 65 secured by bolts 67.

By loosening the nuts on the clamping bolts 61, the shaft 61 may be manually rotated, as by a suitable wrench, and in this manner the direction or position of eccentricity of the off-set end 59 may be conveniently adjusted as desired. The lengths of the chains 49 and the eccentricity are preferably so selected and the direction of eccentricity may be so adjusted that all the slot closing bars 45, except the upper one, are permitted to move to slot closing position by centrifugal action as the housing rotates. The upper slot closing bar 45 is pulled away from the slot 19 by the chain to permit material to be thrown through the upper slot, as shown in Figs. 1 and 2.

Also it is to be understood that the various operating characteristics of my improved material distributing device may be utilized by selecting flexible connectors 49 of various lengths, a shaft 61 having an different eccentricity than shown, and the like. The apparatus, as shown, is represented with the parts in the operative positions assumed with the distributing housing 16 rotating and the slot closing members 45 thrown outwardly by centrifugal force. It is obvious that the device may be operated in either direction of rotation.

It is apparent that within the scope of the invention, modifications and different arrangements may be made other than herein disclosed, and the present disclosure is illustrative merely, the invention comprehending all variations thereof.

I claim:

1. In combination in a material distributing device, a hollow material distributing housing having apertures opening outwardly for delivering material by centrifugal force, said distributing housing being open at one end for receiving material to be distributed and closed at the other end for mounting, a rotatively journaled driving shaft, attaching means for securing the closed end of said distributing housing to one end of said shaft to be thereby supported and rotated, aperture closing members disposed in said housing adjacent the respective apertures for movement
- 5
- 10

15 jacent the respective apertures for movement outwardly by centrifugal force to close the respective adjacent apertures as the housing rotates; a control member mounted in said housing eccentrically with reference to the axis of rotation of said housing, and a flexible connector extending from each aperture closing member to the eccentric control member.

20 the eccentric control member.

2. A material dispersing device having in combination, a rotatable distributing housing, said housing being hollow and having material distributing apertures for delivering material from 25 the center of the housing outwardly as the housing rotates, an axially extending aperture closing member disposed adjacent each aperture to move 30 said outwardly by centrifugal force for closing and opening the apertures as the distributing housing rotates, a control member, bearing means rotatively journaling said control member in the housing eccentrically with reference to the axis 35 of rotation of the housing, said bearing means being adjustable for varying the direction of the eccentricity of the control member, and flexible 40 control means connecting between each aperture closing member and the control member for opening and closing each aperture during respective portions of the circle of rotation of the distributing housing.

3. A material distributing device having in combination, a material distributing housing of a generally hollow conformation having a plurality of openings extending through the housing, and a flexible tube having a proximal end and a distal end, the proximal end being connected to the housing and the distal end being connected to a source of material.

a generally hollow conformation having axially extending slots opening outwardly for delivering material by centrifugal force, a rotatively journalled shaft supporting and driving said distributing housing; slot closing members disposed in said housing adjacent the respective slots for movement outwardly by centrifugal force to close the respective adjacent slots as the housing rotates, a control member mounted in said housing eccentrically with reference to the axis of rotation of said housing, and a flexible connector extending from each slot closing member to the eccentric control member.

4. In combination in a material dispersing device, a hollow material distributing housing having slots opening outwardly for delivering material by centrifugal force, said distributing housing being open at one end for receiving material to be distributed and closed at the other end for mounting, a rotatively journaled driving shaft, attaching means for securing the closed end of said distributing housing to one end of said shaft to be thereby supported and rotated, an axially extending slot closing member disposed adjacent each slot to move outwardly by centrifugal force for closing and opening the slots as the distributing housing rotates, a control member bearing

means rotatively journaling said control member in the housing eccentrically with reference to the axis of rotation of the housing, said bearing means being adjustable for varying the direction of the eccentricity of the control member, and a flexible control means connecting between each

slot closing member and the control member for opening and closing each slot during respective portions of the circle of rotation of the distributing housing.

5. A material distributing device having in combination, a rotatable distributing housing, said housing being hollow and having material distributing apertures for delivering material from the center of the housing outwardly as the housing rotates, aperture closing members disposed in said housing adjacent the respective apertures for movement outwardly by centrifugal force to close the respective adjacent apertures as the housing rotates, a control member mounted in said housing eccentrically with reference to the axis of rotation of said housing, and a flexible connector extending from each aperture closing member to the eccentric control member.

6. A material distributing device having in combination, a material distributing housing of

a generally hollow conformation having axially extending slots opening outwardly for delivering material by centrifugal force, a rotatively journaled shaft for supporting and driving said distributing housing, an axially extending slot closing member disposed adjacent each slot to move outwardly by centrifugal force for closing and opening the slots as the distributing housing rotates, a control member, bearing means rotatively journalling said control member in the housing eccentrically with reference to the axis of rotation of the housing, said bearing means being adjustable for varying the direction of eccentricity of the control member, and flexible control means connecting between each slot closing member and the control member for opening and closing each slot during respective portions of the circle of rotation of the distributing housing.
